(57) **CLAIM**

The ornamental design for an electric ceramic cutting machine as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front elevation view of an electric ceramic cutting machine showing my new design;

FIG. 1.3 is a right-side elevation view thereof;

FIG. 1.4 is a rear elevation view thereof;

FIG. 1.5 is a rear, top, right-side perspective view thereof;

FIG. 1.6 is a front, top, right-side perspective view thereof; and

FIG. 1.7 is a left-side elevation view thereof.

The use of solid red, gold, and copper shading is for the purpose of illustrating contrast in appearance and forms no part of the claimed design.

The grayed areas enclosed by broken lines in FIG. 1.1 illustrate portions of the article that form no part of the claimed design.
